UNITED STATES PATENT OFFICE.

NEWTON FARLEY, OF LILLYBROOK, WEST VIRGINIA.

MINER'S LAMP CLIP AND STAY.

Application filed April 28, 1922. Serial No. 557,081.

To all whom it may concern:

Be it known that I, NEWTON FARLEY, a citizen of the United States, residing at Lillybrook, in the county of Raleigh and State of West Virginia, have invented certain new and useful Improvements in Miners' Lamp Clips and Stays; and I do hereby declare the following to be a full, clear, and exact description of the invention, such as will enable others skilled in the art to which it appertains to make and use the same.

Miners' caps are usually provided at the front with a bracket or plate to which the lamp is attached by means of a hook. To prevent swaying movement of the lamp and to steady and hold it in a given position, a clip or equivalent means is had recourse to and may act jointly with or independently of the attaching hook which generally forms a part of a miner's lamp. The present invention relates to a clip or fastener for attaching a miner's lamp to the lamp bracket, plate or shield of a miner's cap whether said lamp is provided with a suspending hook or is devoid of such hook.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a side view of a miner's cap and attached lamp illustrating the application of the invention,

Figure 2 is a diagrammatic plan view, and

Figure 3 is a detail view of a modified form of clip, the jaws being straight.

Corresponding and like parts are referred to in the following description and designated in the several views of the drawings by like reference characters.

The numeral 1 designates a miner's cap which is provided at the front with a bracket 2 or lamp supporting plate or shield. The numeral 3 designates a miner's

lamp of the type for using carbide, the same having the usual hook 4 for engaging the bracket 2 or like supporting part. These parts may be of any desired construction and are illustrated to demonstrate the application of the invention.

The lamp clip and stay comprises a clamp for engaging the bracket 2 or like part and a holder for receiving the lamp. The clamp comprises a bar 5 having jaws 6 at opposite ends for engaging the edges of the bracket 2 and a bolt 7 or like part passing through openings formed in the jaws 6 and extending along the rear side of the bracket 2, the latter being comprised between the bolt 7 and the bar 5, thereby precluding any possible displacement of the clamp from the bracket after being properly positioned. The bar 5 and jaws 6 constitute parts of a strip of spring metal, said bar curving forwardly more or less according to the contraction of the jaws 6 to grip the bracket 2 by tightening of the bolt or analogous fastening 7. The jaws 6 may be curved, as indicated most clearly in Figure 2, or they may be straight, as shown in Figure 3.

Spaced arms 8 project forwardly from opposite end portions of the bar 5 and may form a part thereof or be provided in any manner.

The hook or holder for receiving the lamp 3 comprises complementary curved members 9 which are hingedly connected at one end, as indicated at 10, and each of which members is hingedly connected intermediate its ends to the respective arms 8.

The members 9 are resilient, being formed of spring metal whereby to readily conform to the lamp 3 and firmly grip the same when in position.

The hinged joint 10 is disposed at the rear of the clip or holder adjacent the clamp and midway between the arms 8 thereof. When the hinge joint 10 is thrown forwardly, the members 9 turn

on their hinge or pivot connections 11 with the arms 8, whereby their outer ends spread to admit of placing the lamp in position between the members 9.

After the lamp has been placed in position, a rearward pressure thereon moves the hinged joint 10 rearwardly, thereby turning the members 9 about their pivots 11 and closing the

same so as to grip the lamp and retain it in position.

The spring action of the clip or holder is facilitated by the resiliency of

the bar 5, the clip operating by a snap action both in engaging and releasing the lamp.

What is claimed is:

- 5 1. Attaching means for a miner's lamp comprising a clamp including a resilient bar having spaced arms projecting therefrom, and a holder comprising complementary members hingedly connected at one end and having hinged connection intermediate their ends to the respective arms whereby the last mentioned hinge connection and resiliency of the bar enable the connected ends of the holder members to move across a line passing through the point of connection of the holder members to the arms.
- 10 2. Attaching means for a miner's lamp comprising a resilient bar having jaws at opposite ends, fastening means connecting the jaws for gripping a miner's cap bracket therebetween, arms projecting from the bar, and oppositely curved lamp gripping members hinged at one end and hinged inter-
- 15

mediate their ends to the respective arms 25 whereby the last mentioned hinge connection and resiliency of the bar enable the connected ends of the holder members to move across a line passing through the point of connection of the holder members 30 to the arms.

3. A device of the class described including a resilient attaching clamp, lamp holder sections, means extending from the clamp and attached to each holder section to 35 mount them in place, said holder sections being pivoted together intermediate their points of mounting, whereby the last mentioned hinge connection and resiliency of the clamp enables the connected ends of 40 the holder members to move across a line passing through the points of connection of the holder members to the said means.

In testimony whereof I affix my signature in presence of a witness.

NEWTON FARLEY.

Witness:

BENNETT S. JONES.
